MOLD FOR TEST CYLINDERS

James W. Rudicil, 504 S. 15th St.,
Blue Springs, Mo.

Filed May 13, 1970, Ser. No. 22,957

Term of patent 14 years

U.S. Cl. D54—8   Int. Cl. D8—99

FIG. 1 is an elevational view of a mold for test cylinders embodying my design.

FIG. 2 is a top view thereof.

FIG. 3 is a transverse cross-sectional view thereof taken on the line 3-3, FIG. 1.

FIG. 4 is a bottom view thereof.

FIG. 5 is a fragmentary cross-sectional view thereof, on an enlarged scale, taken on the line 5-5, FIG. 1.

FIG. 6 is a fragmentary cross-sectional view thereof, on an enlarged scale, taken on the line 6-6, FIG. 3.

I claim:

The ornamental design for a mold for test cylinders, as shown.
